UNITED STATES PATENT OFFICE.

JOHN W. MOORE, OF OAKLAND, OHIO.

FENCE.

SPECIFICATION forming part of Letters Patent No. 512,047, dated January 2, 1894.

Application filed July 18, 1893. Serial No. 480,795. (No model.)

To all whom it may concern:

Be it known that I, JOHN W. MOORE, of 5
Oakland, in the county of Clinton and State
of Ohio, have invented a new and useful Im-
provement in Fences, of which the following
is a full, clear, and exact description.

My invention relates to improvements in
stationary and portable wire fences, that are
composed of series of wire strands arranged
in parallel planes and suitably sustained by
upright posts.

The features embodying my invention are
hereinafter specified and have for their ob-
jects to provide novel connections for the
fence wires, new means for stretching the
wires separately, a new device for anchor-
bracing the fence at the ends, superior means
to compensate for an expansion and contrac-
tion of the fence wires, and a novel method
20 for the support of iron fence posts if these
are used in the construction of the improved
fence.

To these ends my invention consists in the
construction and combination of parts, as is
25 hereinafter described and claimed.

Reference is to be had to the accompanying
drawings forming a part of this specification,
in which similar letters of reference indicate
corresponding parts in all the figures.

30 Figure 1 is a side view of the improved
fence, broken away near one end, showing
one means for connecting the fence wires of
adjoining panels and a new means for erecting
an iron fence post. Fig. 2 is an enlarged
35 side view of portions of two fence wires that
are respectively bent at opposing ends into
double and single loops, and arranged to re-
ceive a locking rod. Fig. 3 is a top view of
the looped ends of the wires shown in Fig. 2.
40 Fig. 4 is an enlarged perspective view of the
ends of two fence wires detachably connected
by novel means; and Fig. 5 is a side view of
portions of two joined fence panels, the ends
45 of the wires of which are looped as repre-
sented in Figs. 2 and 3, to receive a connect-
ing rod.

The posts for the fence may be constructed
of wood, as shown at A, A', in Fig. 1, or may
be made of solid or tubular iron, as repre-
50 sented at B in the same figure. Preferably
at one end of a fence line or panel that is to
be sustained by guys and a post which is an-

chored in the ground, the two fence posts A,
A' are employed, each comprising a wooden
or metal upright that is of a suitable length
to permit an embedment in the earth at one
end, and a projection above the ground far
enough to support other parts of the structure.

For convenience in the attaching of parts
to the posts A, A', the latter are made rect-
angular in cross section above the ground,
any durable wood or metal being utilized in
their manufacture. A sufficient space is al-
lowed between the posts A, A' when these are
erected in a vertical position, and from the
upper end of the post A', that is, suitably re-
moved from the corner post A, two brace bars
a are extended toward the corner post, said
bars being oppositely lapped upon the sides
of the posts named, and thereto secured by
transverse bolts b that are inserted through
aligned perforations in the bars and posts.
The brace bars a are inclined edgewise and
downwardly from the post A' to the point
where they are attached to the post A, so as
to exert a downward pressure on the post A
when draft strain is applied to the upper part
of the post A', in the direction of the post A.

The fence wires C are provided in sufficient
number to suit the desired height of the fence;
as shown, eight fence wires are used, which
are arranged as shown in Fig. 1, the lower
four wires being held spaced apart in closer
order than the upper wires, so as to prevent
the passage between the lower wires of small
animals and fowls. All the fence wires C
pass through perforations in the post A'.

Between the brace bars a the straining bar
D is introduced, which consists of a wooden
or metal strip, rectangular in cross section,
and of a length nearly equal to the height of
the fence posts A, A' above the ground.
There is a number of similar eye-bolts c,
loosely inserted in transverse perforations in
the straining bar D, the distances between
these perforations of the bar representing the
spaces between the fence wires C. The ends
of the wires C that extend toward the straining
bar, are connected to the ring eyes formed
on the eye-bolts that are equal in number to
the fence wires, and a threaded nut c' that is
placed on the screw-cut body of each eye-bolt
so as to bear upon the side of the straining
bar which is nearest to the post A, affords

means to alter the adjustment, for length, of each bolt independently of others of the series.

The several wire strands C of a fence panel 5 are spaced apart by the vertically arranged pales E, E', which are located at correct distances of separation and are each attached to the wires by staples or equivalent means, as indicated at d in Fig. 1. Preferably, the pales E are made of a length which will permit them to be connected to all of the wires C, the pales E' being shorter and serving to sustain the four lower wires in a spaced condition between the longer pales.

The wires C of a fence panel, of which the posts A, A' are portions, have their terminals which are farthest removed from the post A, connected to a similar series of wires that are portions of another fence panel, preferably 5 by means of their interlocking looped ends shown in Fig. 4, another style for such looped connections being represented in Figs. 2, 3 and 5.

The wire connecting device shown in Fig. 5 4 consists of an elongated loop e, formed on each wire strand that is to be connected, by return bending the end portion and twisting the end around the body of the wire, and when two of these loops are to be detachably 5 interlocked with each other, it is only necessary to pass one loop through the other and bend the inserted loop portion into hook form, the folded part of the inserted looped end e' being then introduced between the two strands 5 of said loop to produce an eye, which will afford a reliable connection between the ends of the wires C, and similar treatment of each aligned pair of wires belonging to two adjacent fence panels, serves to detachably secure the series of wires in one panel to those of the panel next in sequence, for the continuous erection of a fence of any desired length. The interlocking connection of the looped ends e, e', may be effected before or after the erection of the fence.

The end of a fence line, of which the post A is the terminal, is elastically secured to said post by the use of two coupling bolts g that are introduced into opposite perforations 5 made for each bolt in the post A and straining bar D, these bolts each having a nut on the threaded end portion that projects through and beyond the post A. A sufficient space intervenes the straining bar D and post A, 5 to permit a spacing strip F to be introduced between them and be stapled fast to the bodies of the bolts g, this bar aiding to close up the space between the parts A, D, sufficiently to prevent the passage of small animals or 5 fowls through the same.

On the parts of the bolts g that extend beyond the straining bar D, toward the post A' and between pairs of the eye-bolts c, a strong spiral spring h is located on each bolt, 5 the length of the springs being equal and such as will adapt them to occupy the entire projecting bolt portions, whereon they are re-

tained by a nut and washer g², that when in place slightly compress the springs so as to render the fence wires taut. A guy rod i is 70 furnished, this being formed of a single bent rod that is loosely engaged at its fold with an eye-bolt m, that extends through a diagonally formed perforation in the post A', near its upper end, and is secured therein by a nut 75 m'; the equal members of the rod are extended each side of the fence panel, and beyond the post A have their end portions secured to the anchor post G that is made of wood, or other suitable material. The guy 80 rod i may also consist of wire rope of a proper gage to suit the purpose.

The preferred means for attaching the guy rod i to the anchor post or block G, consists in the insertion of their ends through the latter and screwing nuts on these threaded portions of the rods.

As shown in Fig. 1, the anchor post G is embedded a sufficient distance in the ground to render it stable, the body being inclined 90 away from the post A, which will conduce to its stability when subjected to draft strain produced by tightening the nuts on the ends of the guy rod and eye-bolt m.

The post B, previously mentioned, that represents the terminal of the fence line farthest from the anchor post G, may be made of wood in the form represented by the post A, or be a metallic post that may be tubular to lighten it; the guy rod n that is similar to the rod i, 100 being in a like manner connected to the eye-bolt o that extends diagonally through the post, near its upper end, and is secured in place by a nut o', the lower ends of the members of the guy rod being attached to an anchor block, not shown, similar in form to the post or block G. The fence wires C, can also be inserted through spaced holes in metal posts B, if such are used in place of wooden posts, or staples may be secured to posts such 110 as B to hold the wires spaced apart.

The fence wires C are connected to the post B by any preferred means. Preferably, the post B if formed of metal, is maintained in a vertical position in the ground by the employment of a base piece I, that is, a section of concrete or terra-cotta tube such as is used for drain pipe, this being embedded at a proper point in the ground, so as to receive the lower portion of the post that is of less diameter 115 than the base piece, affording an annular space between their circular walls that is filled with cement in a plastic condition, the subsequent hardening of the filling serving to unite the post and base piece, thereby providing an enlarged base for the post that is not liable to corrode the post or release it.

The coupling device for the ends of the fence wires C, which is represented in Figs. 2 and 3, detached, and in a connected condition in Fig. 5, comprises a double loop p, that is bent from an end portion of one fence wire and a single loop p' that is bent on the other wire which, in service, is aligned with the first men-

tioned wire; the single loop being slid between the spaced members of the double loop, so that a locking rod *r* may be inserted through each pair of double and single loops 5 and thus detachably connect all the wire strands of two adjacent fence panels.

It will be seen that, if desired, the fence constructed as hereinbefore explained may be removed from one place and erected in another, and that, by the adjustment of the several parts, as described, a substantial fence may be quickly erected which will serve as a reliable barrier against the escape of animals or fowls within its inclosure, or prevent the encroachment of large or small animals from without its boundary.

Having thus described my invention, I claim as new and desire to secure by Letters Patent—

20 1. In a wire fence, the combination with aligning posts near one end, of a panel, parallel brace bars bolted on the sides of the posts and inwardly inclined from the inner post to the outer post, a guy rod formed from a rod or 25 twisted strands of metal, an adjustable eye-

bolt engaging the bend of the guy rod and passing through the inner post, and an anchor post engaged by the ends of the members of the guy rod which ends are adjustable in said post, substantially as described. 30

2. In a wire fence, the combination with aligning posts near one end, of a panel, and brace bars oppositely secured on said posts and downwardly inclined from the inner post toward the outer post, of a series of fence wires, spacing pales thereon, a straining bar, eye-bolts engaging said bar and connected to ends of the fence wires, coupling bolts threaded at each end and passing through the straining bar and outer post, nuts thereon, spiral 35 springs on the inner ends of the coupling bolts and bearing on the straining bar, a post at the other end of the fence line, and guy rods adapted to spread the outer posts of the fence line, substantially as described. 40
